FOAM-PRODUCING APPARATUS

Wilfred James Clifford and Henry Heward Adams, Brentford, England, assignors to The Pyrene Company Limited, Brentford, England, a British company

Application March 19, 1945, Serial No. 583,520
In Great Britain March 27, 1944

8 Claims. (Cl. 261—94)

1

This invention relates to the production of air foam by forcing water, a foam-forming liquid and air or other gas through a mixing body of the labyrinth type. As set forth in Clifford's application Serial No. 409,526, filed September 4, 1941, now Patent No. 2,376,122, dated May 15, 1945, it is desirable for the water (either mixed with or separate from the foam-forming liquid) to be supplied under a constant head that is independent of the pressure of the air or other gas. In the apparatus described in said application No. 409,526 the constant head is produced by either an air-lift device or a pump delivering to a vessel in which the liquid is maintained with a free surface under the same air or gas pressure as that applied to the mixing body, or the head is allowed to form by gravity under the control of a float-operated valve. This apparatus is effective, but the former types are somewhat complex and the latter type takes up more space vertically than is desirable.

It is the primary object of this invention to provide a simpler and more compact form of apparatus for supplying the liquid under a constant head.

Another object of this invention is to provide an improved apparatus for producing foam for fire-extinguishing, dust-allaying or other purposes.

Fig. 1 is a schematic view intended to illustrate the principle of Mariotte's bottle;

Fig. 2 is a view, largely in vertical section and partly in elevation, showing one form of apparatus embodying the present invention for the production of fire extinguishing foam;

Fig. 3 is a schematic view of a modified form of apparatus embodying the invention, the tank forming part of this apparatus being shown only in part and in section;

Fig. 4 is a view similar to Fig. 3 showing a further embodiment of the invention;

Fig. 5 is a schematic view illustrating a still further embodiment of the invention, the tank forming part of the apparatus being shown in vertical section and other parts being only schematically indicated; and

Fig. 6 is a view in vertical section through apparatus constituting still another embodiment of the invention.

Essentially in the present invention use is made of the principle of operation of what is known as Mariotte's bottle. This principle is illustrated by Fig. 1 of the accompanying drawings, which shows a closed container 1 into which air can flow through the pipe 2, the lower open end 3 of which

2

is immersed in water 4. This water can escape through an orifice 5 at the bottom under the control of a valve 6. The pressure P at the orifice 5 does not vary with the level of the water in the container. The reason is that the pressure in the space above the water is the air pressure A (in cms. of water) less the distance H_2 (in cms.) between the water level and the opening 3. The head at the orifice 5 is therefore $A - H_2 + H_1$, where H_1 is the distance between the water level and the orifice. But if H_3 is the distance between the opening 3 and the orifice 5, $H_3 = H_1 - H_2$, so that $P = A + H_3$. Granted, therefore, that there is a constant pressure of air at the top of the tube 2 and that the opening 3 is immersed in water the pressure at the orifice will depend only on the distance between the opening 3 and the orifice 5.

In the production of apparatus working in this principle in the present invention the water or solution of foam-forming liquid is placed in a closed tank or other container which corresponds to the closed vessel 1, and is led directly to the mixing body from a point in the container at or near to the bottom. The air or other gas is not only led to the inlet to the mixing body but also is introduced through an opening or openings above the point at which the liquid and gas meet on their way to the mixing body but below the liquid level and low enough to ensure that most of the liquid will run out of the container before the level of the liquid falls to that of the opening or openings. The effective head H_3 is the distance between the opening or openings and the point at which the liquid and gas meet in flowing to the mixing body. The opening or openings should be at only a short distance above the point at which the liquid and gas meet, that is to say, the distance H_3 is preferably made small, because otherwise the opening or openings will be uncovered before most of the liquid has run out of the container. When the opening or openings are uncovered foam will continue to be formed until the inlet to the mixing body is uncovered, but the pressure will then no longer necessarily be constant. To ensure that the maximum amount of liquid is discharged under a constant head the liquid and gas should meet at as low a point in the container as possible. The liquid below the inlet to the mixing body is not converted into foam, so in order to utilise the contents of the container to the full the inlet to the mixing body should be as low as possible.

The apparatus shown in Figure 2 comprises a container 10 holding, for example, 200 gallons of water containing a foam-forming liquid in solu-

3
tion. A mixing body 11, composed of randomly packed small pieces of metal tube or other appropriate material, is housed in a vertical tube 12 and supported at the lower or entrance end by a grid 13. A second tube 14 surrounds the tube 12. Both tubes extend vertically through the container 10 and out through the top of it. Air is introduced into the space between the tubes through a pipe 15 controlled by a valve 16. Openings 17 are made in the tube 14, and are 10 shrouded by a hood or bell 18 secured to the tube 14. The lower edge of this hood or bell lies far enough below the row of openings 17 to provide an air lock through which the air can pass into the main part of the container.

The tube 14 is open at its lower end and has an inturned flange 19, and liquid passes from the body of the container through the aperture within this flange. A foam-discharge pipe 20 is connected to the upper end of the tube 12.

In operation air under pressure is supplied through the pipe 15 and the bulk of it flows down the space between the tubes 12 and 14 to the bottom and then turns upwards and flows through the mixing body. Some of the air, however, passes through the openings 17 under the lower edge of the bell 18 into the body of liquid to rise into the space above.

It will be seen that in this apparatus the distance H_3 is that between the lower edge of the bell 18 and the point just above the aperture at the bottom of the tube 14 where the liquid and air meet to flow into the tube 12.

In the modification shown in Figure 3, the mixing body 11 is outside and below the container 10. It is housed in a bent tube 21 which extends upwards for a short distance through the bottom of the container. The liquid flows from the container 10 through a row of apertures 22 made in the tube 21 just above the bottom of the container. The air is introduced through a pipe 23 which enters the pipe 21 and then is bent to run coaxially with the vertical part of it, terminating just short of its open end. This open end of the pipe 21 is shrouded by a bell or hood 24.

The modification shown in Figure 4 closely resembles that of Figure 2 and differs only in that the lower ends of the tubes 12 and 14 lie in a well 25 which extends below the general level of the bottom of the container 12. With this arrangement the whole volume of the liquid in the container except only that in the well can be converted into foam, and as the bell 18 lies only just above the bottom of the container substantially all the foam will be delivered under constant pressure.

Figure 5 shows an apparatus suitable for producing foam for allaying the dust which arises during rock-drilling operations. For this purpose the total volume of foam required is relatively small, and a container 26 of, say, five gallons capacity, is used. The mixing body 11 is arranged in a tube 12 in the same way as in Figure 2 and is surrounded by a tube 14 which carries an air bell 18. In this apparatus it is convenient to be able to vary the flow of liquid to the mixing body and this is done by providing a conical valve 27 on the end of a spindle 28 which extends axially through the mixing body and is provided with an operating knob or handle 29 outside the mixing body. Naturally the size of an aperture through which the liquid flows to the mixing body can be controlled in the other apparatus in the same way if desired.

Another way of controlling the flow of liquid 75

is to vary the height of the column of liquid which is added to the air pressure to give the constant head, and this may be done by providing a series of openings with a sleeve valve or the like for uncovering whichever is desired or by making an air bell or hood vertically adjustable. One such apparatus is shown in Figure 6, in which a tube 36 terminates at the same level as a tube 12 containing the mixing body 11 and carries an air bell 37 formed with openings 38 at different levels. A cup-shaped member 39 fits inside the air bell 37 and is formed with openings 40 at levels corresponding to those of the openings 38 but spaced around the member 39 so that in different angular positions of the air bell 37 and member 40 openings at different levels are brought into register with one another. The number 39 is formed with apertures 41 through which liquid can flow from the interior of the container 10 to the mixing body 11 and it is fixed to a spindle 42 which extends vertically through the mixing body. The spindle 42 is provided with an operating knob 43 by which it can be turned to vary the angular position of the member 39 within the air bell 37 and thus to bring the desired opening 38 into register with the desired opening 40. By this means the distance H_2 can be increased and the distance H_3 correspondingly decreased from those shown in Figure 6.

It will be understood that in all the apparatus the passage ways for the air or other gas are made large enough to ensure that for practical purposes the pressures at the point where the liquid and gas streams meet and at the air bell are the same as that at the gas inlet.

4
A fire extinguishing apparatus such as that shown in Figure 2 is usually discharged only once, and then the discharge is continuous. For the purpose of allaying dust, however, an apparatus capable of being stopped and restarted is required. 40 Now if the main foam outlet valve (not shown) is turned off to stop the flow, the pressure in the apparatus will increase above that normally occurring during running. When the outlet valve is opened again, the pressure acting upon the mixing body will not be that produced by the constant head alone, but also that of the excess of the pressure in the space above the liquid over the pressure in the remainder of the apparatus, which will have fallen to the running pressure. 50 Accordingly in such an apparatus as that shown in Figure 5 it is desirable to provide a bleeding valve in the space above the liquid, as shown at 30. This valve is set to allow air to escape continuously and its opening is small in relation to the air passage ways, so that in normal operation it does not produce any reduction in the pressure in the space above the liquid, but when the foam outlet valve is closed it does serve to prevent such an increase in pressure as would materially affect the operation of the apparatus.

55 We claim:

1. Apparatus for producing foam which comprises a closed storage tank adapted to retain a 60 foam forming solution, a labyrinth type mixing chamber in said tank, gas retaining means surrounding said mixing chamber, means for introducing solution from said tank into said mixing chamber, means for supplying gas under pressure to said gas retaining means, means for delivering gas from said retaining means in part to said tank and in part to said mixing chamber, said last mentioned means including a cup member 65 cooperating with said mixing chamber and said gas retaining means to direct the gas along

the two paths indicated, and means for delivering foam formed in said mixing chamber to a point exterior of the tank.

2. Apparatus for producing foam which comprises a closed storage tank adapted to retain a foam forming solution, said tank having an outlet port adjacent its bottom, means for introducing a gas under pressure into the solution in said tank at a point at a predetermined level above said outlet port, a labyrinth type mixing chamber, means for delivering solution through said outlet port to said mixing chamber, means for varying the level at which said gas is introduced into the solution in said tank and thereby varying the rate at which said solution is delivered to said mixing chamber, and means for introducing gas under pressure into said chamber.

3. Apparatus for producing foam which comprises a closed storage tank adapted to retain a foam forming solution, a tubular member extending into the bottom of said tank, said member being apertured at a point within said tank adjacent its bottom for the discharge of solution from said tank, a mixing chamber connected with said member and arranged to receive the solution therefrom, and means for delivering gas under pressure through the interior of said tubular member, said member being open at its upper end and having a bell shrouding the same, the arrangement being such that a portion of the gas delivered by said means is enabled to pass from said bell into the solution and a portion of said gas is directed into said member and said mixing chamber.

4. Apparatus for producing foam which comprises a closed storage tank adapted to retain a foam forming solution, said tank having an outlet port for said solution adjacent its bottom, a gas supply means, means for introducing a gas under pressure from said supply means into the solution in said tank at a point below the upper surface thereof at a predetermined level above said outlet port, a labyrinth type mixing chamber, means for delivering solution discharged through said outlet port to said mixing chamber, and means for introducing gas from said supply means under pressure directly into said outlet port, said last recited means being arranged to provide a gas retaining enclosure around said outlet such that the gas therein opposes the flow of solution to said outlet.

5. Apparatus for producing foam which comprises a closed storage tank adapted to retain a foam forming solution, said tank having an outlet port adjacent its bottom, a gas retaining member, means for introducing a gas under pressure from said member into the solution in said tank at a point at a predetermined level above said outlet port, a labyrinth type mixing chamber, means for delivering solution discharged through said outlet port to said mixing chamber, and means for delivering gas under pressure from said retaining member directly to the region of said outlet port.

6. Apparatus for producing foam which comprises a closed storage tank adapted to retain a foam forming solution, a labyrinth type mixing

chamber in said tank, a gas retaining member surrounding said mixing chamber, means adjacent the bottom of said tank for placing the solution in said tank in communication with said mixing chamber, means for supplying gas under pressure to said gas retaining member, means for delivering gas from said retaining member in part to the solution in said tank at a point above said first mentioned means and in part to said mixing chamber, and means for delivering foam formed in said mixing chamber to a point exterior of the tank.

7. Apparatus for producing foam which comprises a closed storage tank adapted to retain a foam forming solution, said tank having an outlet port adjacent its bottom, gas supplying means, means for introducing a gas under pressure from said supply means into the solution in said tank at a point above said outlet port, a labyrinth type mixing chamber, means for delivering solution from said tank through said outlet port to said mixing chamber, means for varying the rate at which said solution is delivered to said mixing chamber, and means for introducing gas under pressure into said chamber, said last recited means providing a partial enclosure in association with said outlet port in which said solution and gas are brought together.

8. Apparatus for producing foam which comprises a closed storage tank adapted to retain a foam forming solution and having a gas space above the solution, said tank having an outlet port adjacent its bottom, gas supply means, means including a gas receiving member connected with said supply means for introducing a gas under pressure into the solution in said tank at a predetermined level in relation to said outlet port, a labyrinth type mixing chamber, means for delivering solution through said outlet port to said mixing chamber, said last recited means providing a partial enclosure in association with said outlet port, means for introducing gas under pressure from said supply means to said partial enclosure and into said mixing chamber, means operable at will for varying the character of the foam and the rate at which it is discharged from said mixing chamber, and means for relieving the pressure within said gas space when the pressure therein rises above a predetermined amount.
